(57) **CLAIM**

The ornamental design for a wall mount for audiovisual apparatus, as shown and described.

DESCRIPTION

FIG. 1 is a perspective view of a wall mount for audiovisual apparatus showing my design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a front view thereof with an inserted audiovisual apparatus shown in broken lines.

The broken lines in the figures show use of the wall mount for audiovisual apparatus and form no part of the claimed design.
